(57) **CLAIM**

The ornamental design for a grip cover with laser sight, as shown and described.

DESCRIPTION

FIG. 1 is a front and right side view of a grip cover with laser sight showing my new design attached to a pistol;

FIG. 2 is a front and left side view thereof attached to a pistol;

FIG. 3 is a right side elevational view thereof;

FIG. 4 is left side elevational view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a top, front, and left side view thereof;

FIG. 10 is a bottom, rear, and right side view thereof;

FIG. 11 is a right side elevational view of an alternative embodiment of my new design;

FIG. 12 is a left side elevational view thereof;

FIG. 13 is a front elevational view thereof;

FIG. 14 is a rear elevational view thereof;

FIG. 15 is a top plan view thereof;

FIG. 16 is a bottom plan view thereof;

FIG. 17 is a top, front, and left side view thereof; and,

FIG. 18 is a bottom, rear, and right side view thereof.

The dashed lines in the drawings are used to illustrate unclaimed portions of the claimed design and unclaimed environment in FIGS. 1 and 2, and form no part of the claimed design.

1 Claim, 6 Drawing Sheets
